UNITED STATES PATENT OFFICE

CLARENCE G. JOHNSON, OF HARTFORD CITY, INDIANA

SEALING STRIP CONSTRUCTION

Application filed July 23, 1928. Serial No. 294,885.

This application is a continuation in part of my copending Patent No. 1,824,212 of September 22, 1931. The object of the invention, as in the patent, is to provide a sealing device which operates automatically when a 5 slideable closure member is moved to its closed position. The particular closure member described and illustrated herein is a sliding window sash.

10 Another object of the invention is to provide a sealing device which automatically comes into operation when the sashes are moved to closed position, in order to prevent rattling of the sashes and loss of heat through 15 the window.

The invention includes, in conjunction with the sashes, sealing strips pivotally attached to the frame. Springs acting on these strips tend to project one end thereof into 20 the path of the sashes. When the latter are moved to closed position, they engage the projected ends and turn the strips on their pivots so that they come into longitudinal engagement with the sashes.

25 The invention is fully disclosed in the following description and in the accompanying drawing in which—

Figure 1 is a fragmentary front elevation of a window equipped according to the invention;

Fig. 2 is a vertical section thereof showing the sashes in closed position;

Fig. 3 is a vertical section showing the sashes in open position; and

Fig. 4 is a detailed section on the line 4—4 of Fig. 2.

Reference to these views will now be made by use of like characters which are employed to designate corresponding parts throughout.

40 In the several figures is illustrated a window of the conventional sliding sash or double-hung type comprising a frame 1 in which a lower sash 2 and upper sash 3 are slidably mounted and guided by parting strips 4.

45 In the lower part of the frame is mounted a pair of sealing strips 5 each turning on a pivot pin 6 passed through the lower portion thereof and into the adjacent jamb. At the upper part of each strip is a short transverse slot 7 through which passes a pin 8

entering the jamb. The upper or free ends of the strips are joined each by an expanded spring 9 to the adjacent jamb, whereby the lower ends 10 of the strips are projected into the path of the sash 2.

In like manner the pair of sealing strips 11 are hung in the upper part of the window frame on the projected pins 12 entering the adjacent jamb. The lower part of each such strip has a transverse slot 13 penetrated by a pin 14 entering the jamb. Springs 15 connect the lower ends of the strips to the frame and thus tend to move the upper or pivoted ends 16 into the path of the upper sash 3.

When either of the sashes is moved to closing position it engages the ends of the strips projecting into its path and, in moving these ends out of its path, swings the strips on its pivots. The movement of the strips is in the direction towards the sash which actuates them, and the strips thereby come into longitudinal engagement with the sashes, as shown in Fig. 2, so that the latter are held firmly against the parting strips 4 and also sealed by the strips.

Although a specific embodiment of the invention has been illustrated and described, it will be understood that various alterations in the details of construction may be made without departing from the scope of the invention as indicated by the appended claims.

What I claim is:—

1. A window construction comprising a frame, a sash slidably mounted therein, and a sealing strip pivotally attached intermediate its ends to said frame and having a free swinging movement at both sides of the pivotal attachment, and a spring connecting one end of said strip to said frame whereby to project the other end into the path of said sash.

2. A window construction comprising a frame, a pair of sashes slidably mounted therein, sealing strips pivotally attached intermediate their ends to said frame, each strip having a free swinging movement at both sides of its pivotal attachment, and springs connecting said strips to said frame whereby to project a part of each strip into the paths of said sashes.

3. In combination with a frame and a closure member slidably mounted to cover and uncover the frame, sealing strips pivoted to said frame intermediate their ends and each having one end adapted to project into the path of said closure member in the closing movement thereof, whereby such closing movement swings the remaining ends of said strips against said closure member.
- 10 4. In combination with a frame and a closure member slidably mounted to cover and uncover the frame, sealing strips pivoted to said frame intermediate their ends and each having one end adapted to project into the path of said closure member in the closing movement thereof, whereby such closing movement swings the remaining ends of said strips against said closure member, and springs acting on said strips for positively projecting the first named ends into said path.
- 15
- 20

In testimony whereof I affix my signature.
CLARENCE G. JOHNSON.
